(57) **CLAIM**

The ornamental design for a connecting terminal assembly,
as shown and described.

DESCRIPTION

FIG. 1 is a perspective view of my design for connecting
terminal assembly;

FIG. 2 is a side elevational view of my design for a
connecting terminal assembly;

FIG. 3 is another side view opposite that shown in FIG. 2 of
my design for connecting terminal assembly;

FIGS. 4 and 5 are opposite end elevational view of my
design for connecting terminal assembly;

FIG. 6 is a top plane view of my design for connecting
terminal assembly; and,

FIG. 7 is a bottom plane view of my design for connecting
terminal assembly.
